MORTIMER R. RUST, OF FULTON, NEW YORK, ASSIGNOR TO DILTS MACHINE WORKS, INC., OF FULTON, NEW YORK, A CORPORATION OF NEW YORK.

BEATER ROLL AND BAR.

1,368,757.

Specification of Letters Patent. Patented Feb. 15, 1921.

Application filed November 17, 1919. Serial No. 338,444.

To all whom it may concern:

Be it known that I, MORTIMER R. RUST, citizen of the United States, residing at Fulton, in the county of Oswego and State of New York, have invented certain new and useful Improvements in Beater Rolls and Bars, of which the following is a specification.

This invention relates to beater rolls and bars which are intended for use in beating engines employed to act upon rags, wood pulp or other fibrous stock in the manufacture of paper.

In the construction of beating engines, it is especially desirable that the fly bars shall be effectively and easily secured in the roll heads, and it is an object of this invention to produce a roll head, fly bar and securing means having parts of special construction and arrangement whereby it is believed the fly bars may be quickly and firmly secured and kept fast, and as expeditiously removed for replacement or repairs.

To illustrate the particular formation and disposition of the parts comprising this invention, the accompanying drawings are made a part of this application. Figure 1 represents an interior end view of a portion of the roll head to which this invention is applied. Fig. 2 is a top plan view of a portion of a roll head and bar constructed in accordance with this invention. Fig. 3 is a top plan view of the wedge. Fig. 4 is a vertical cross-section of the wedge on broken line 4—4 of Fig. 3. Fig. 5 is an end view of a fly bar constructed in accordance with this invention.

Throughout the drawings and description the same letter is used to refer to the same part, and in the drawings Figs. 3, 4 and 5 are illustrative of the parts in full size.

Considering the drawings, the roll head A has an annular shoulder *a* on the inside of the roll head, and it has a succession of peripheral radially projecting blocks B spaced apart leaving recesses *b* between them.

As best shown in Fig. 2 one wall C of each recess extends perpendicularly across the roll, and the opposite wall *c* diverges and

lies across the roll in a slanting direction. Both walls of the recess incline from the mouth of the recess to the bottom, whereby the bottom of the recess is the widest part thereof. The annular shoulder *a* may be *ar*, 55 ranged flush with the bottoms of the recesses. Both sides of head A may have a shoulder.

As best set out in Fig. 5, the fly bar D has the flat side *d*, and an angular side comprising the two beveled sides or surfaces *E* and *e*. At the foot F of the fly bar, and terminating the beveled side *e* at its lower edge is the shoulder *f* extending longitudinally of the bar. The shoulder *f* may be given a 65 slight inclination as illustrated, and for the purpose hereinafter stated, but it will be understood that it is not intended to confine this invention to the precise surface inclinations in position or extent as shown in 70 the drawings.

The remaining element or member of the combination comprising this invention is the wedge G, illustrated in Figs. 3 and 4. The wedge has the top *g*, the inclined sides 75 *H* and *I*, and the bottom *J* provided with the portion *j* arranged to engage the shoulder *f* of the bar as shown in Fig. 1.

In the operation, the fly bar is placed in a recess with its flat side *d* against the side 80 wall C of the recess, this wall being the one described as extending perpendicularly across the roll head. It will be understood that the wall C inclines from top to bottom of the recess, diverging from the opposite 85 wall *c*, and the meaning of the description stating that the wall C extends perpendicularly across the roll head is that the edge of the wall C, or any line upon it parallel with the edge is perpendicular to the sides of the 90 head. The side of the fly bar having the shoulder *f* lies within the recess, and that wall of the recess marked *c* converges with respect to the bar from the inner to the outer side of the roll head. Both walls of 95 the recesses *b* incline toward each other from the center of the head, and diverge toward the bottoms of the recesses, the bottoms being the widest parts. Thus, the recesses may be described as wedge-shaped 100

transversely of the head and of dovetail form as shown in Fig. 1. The wedge is inserted between the beveled side *e* of the fly bar, and the inclined wall *e* of the recess, 5 and the inclined portion *j* of the bottom of the wedge is arranged against the shoulder *f* of the fly bar. As the wedge is driven in, it presses the bar against the side wall *C* of the recess, and by reason of the engagement with the shoulder *f* the portion *j* of the wedge forces the foot of the bar downwardly against the bottom of the recess, or against the annular ring *a*. The wedges may be conveniently tightened at any time, 10 and the fly bars are always firmly held. It is believed to be clear that any individual fly bar may be removed and replaced by removing the wedges securing it, and that no special tools are required to perform such removal or replacement. The fly bar set out hereinabove has been described as having one flat side and a doubled beveled side, but, 15 it is not intended to limit this invention to that form.

25 Having now described this invention and explained the mode of its operation, what I claim is:—

1. In a beater roll and bar, the combination with a roll head having peripheral radially projecting blocks spaced apart leaving recesses between them, one side wall of each of the said recesses being inclined from the mouth of the recess whereby the bottom of the recess is the widest part thereof, the 30 said recesses being wider on one side of the roll head, of fly bars each having a beveled side and a longitudinal shoulder terminating the said beveled side at its lower edge, and a wedge constructed to engage the said inclined wall of the recess and the beveled side of the fly bar, the bottom of the wedge 35 having a portion arranged to engage the said shoulder of the fly bar.

2. In a beater roll and bar, the combination with a roll head having peripheral radially projecting blocks spaced apart leaving recesses between them, one side wall of each recess extending perpendicularly across the head and one of the walls extending 40 slantingly across the head, one of the side walls of each recess being inclined from the mouth of the recess whereby the bottom of the recess is the widest part thereof, of fly bars each having a beveled side and a longitudinal shoulder terminating the said beveled side at its lower edge, and a wedge constructed to engage the said inclined wall 45 of the recess and the said beveled side of the fly bar, the said wedge having a portion constructed to engage the said shoulder of the fly bar whereby the bar is forced against the bottom of the recess, or against an annular ring and against the said perpendicular side wall of the recess.

65 3. In a beater roll and bar, the combina-

tion with a roll head having peripheral radially projecting blocks spaced apart leaving recesses between them, one of the said walls of each recess extending perpendicularly across the head, both of the side walls 70 of each recess being inclined from the mouth of the recess whereby the bottom of the recess is the widest part thereof, the said walls of the recess converging toward each other across the head from the inner to the outer 75 side thereof, of fly bars each having a beveled side and a longitudinal shoulder terminating the said beveled side at its lower edge, and a wedge constructed to engage the inclined walls of the recess and the beveled side of the fly bar, the said wedge having a portion arranged to engage the said shoulder of the fly bar.

4. In a beater roll and bar, the combination with a roll head having peripheral radially projecting blocks spaced apart leaving recesses between them, one wall of each recess being inclined from the mouth of the recess whereby the bottom of the recess is the widest part thereof, of fly bars each having 90 a beveled side and a longitudinal shoulder terminating the said beveled side, and a wedge arranged to engage the said inclined wall of the recess and the beveled side of the fly bar and the said shoulder of the fly bar, 95 the said side wall of the recess and the beveled side of the fly bar being formed divergently with respect to each other.

5. In a beater roll and bar, the combination with a roll head having transverse 100 wedge-shaped and dovetail recesses and an annular internal or external shoulder, of fly bars resting upon the said annular shoulder or upon the bottom of the recess, and each fly bar having a beveled side and a longitudinal shoulder connected with the said beveled side of the bar, and a wedge engaging the side of the recess and the beveled side of the bar and the said shoulder of the bar.

6. In a beater roll and bar, the combination with a roll head having transverse 110 wedge-shaped and dovetail recesses and an annular shoulder, of fly bars resting upon the said shoulder and each fly bar being provided with a side having a longitudinal shoulder, and a wedge engaging the side of the recess and the side of the bar and the said shoulder of the bar.

7. In a beater roll and bar, the combination of a roll head having slots or recesses 120 for fly bars with the side walls so inclined that the said slots or recesses are wider at the bottom than at the outer periphery of the roll head, one side wall of each recess or slot being at right angles to the roll head, or in other words, in a plane which is parallel to the axis of the roll, the other side wall of each said slot or recess extending slantingly across the roll head or in a plane which is at an angle to the axis of the roll, 125 130

said angle being such as to make the slot thus formed wider at one side of the roll head than at the other side, and fly bars having a longitudinal shoulder at the lower edge, and wedge constructed to engage the said inclined walls of the slots or recesses as well as the side and shoulders of the fly bars,

whereby the bars are forced against an annular ring, or against the bottom of the slots or recesses, and against the said parallel side 10 wall of the recesses.

In testimony whereof I affix my signature.

MORTIMER R. RUST.
